UNITED STATES PATENT OFFICE.

JOHN G. WARFIELD, OF LOS ANGELES, CALIFORNIA, ASSIGNOR OF ONE-FOURTH TO
C. R. HARRIS, OF LOS ANGELES, CALIFORNIA.

EDUCATIONAL APPLIANCE.

967,591.

Specification of Letters Patent. Patented Aug. 16, 1910.

Application filed July 14, 1909. Serial No. 507,589.

To all whom it may concern:

Be it known that I, JOHN G. WARFIELD, a citizen of the United States, residing at Los Angeles, in the county of Los Angeles and State of California, have invented certain new and useful Improvements in Educational Appliances, of which the following is a specification.

My invention relates to an improvement in educational appliances, the object being to provide means whereby a cylinder having columns of figures thereon can be rotated, whereby the columns of figures will be presented to view through an opening in an upright to permit of the columns of figures being added.

A further object is to provide means whereby a long or short column of figures may be exposed at the will of the operator.

The invention consists in certain other novel features of construction and combinations of parts which will be hereinafter described and pointed out in the claim.

In the accompanying drawings:—Figure 1 is a perspective view, Fig. 2 is a vertical sectional view, Fig. 3 is a cross section, and Fig. 4 is a detail sectional view, showing the manner of applying or connecting the sheets on the cylindrical body.

A, represents the base, and B is an upright connected thereto, which is provided with a vertical slot 1. Flanges or guides 2, 2, are connected to the inner side of the upright B, and a slide 3 passing through the top of the upright is received between the flanges and upright, the flanges forming guides for the slide in its movement. A concave opening 4 is formed in the base A, in which is received a convex bearing 5 on the bottom 6, of the cylindrical body or member 7. The bottom 6 is preferably made of wood, and the cylindrical body 7 of heavy card-board. Hoops 8 are received within the cylindrical body 7 at certain intervals for forming proper support for the body. Buttons or knobs 9 are formed along the upper and lower edges of the cylindrical body 7, whereby the cylinder can be rotated upon the base A.

Removable sheets of cardboard 10 having columns of figures thereon are connected

to the cylindrical body 7 in any approved manner, but I have shown them held by the buttons 9. The buttons can either be removed from the cylinder for connecting the sheets thereto, or the sheets can be slipped over the buttons by providing the sheets with slits or openings 11.

The cylinder or member 7 is rotated upon the base A, bringing the desired column of figures into view through the slot 1 of the upright B. The slide 3 can be moved to any position for varying the length of the column, and exposing any desired number of figures, for instance four or five figures can be exposed, at a time, for the purpose of adding, or a greater or less number can be exposed by shifting the slide. A device of this character is intended to be used more particularly in schools for the purpose of teaching addition, and by providing columns of figures differently arranged upon the sheet, the pupil will thereby become familiar with the different numerals, and the result of these different numerals when added together. As the sheets 10 are capable of being removed, new sheets can be supplied and applied to the cylinder.

It is evident that more or less slight changes might be resorted to in the form and arrangement of the several parts described without departing from the spirit and scope of my invention, and hence I do not wish to be limited to the exact construction herein set forth, but:

Having fully described my invention, what I claim as new and desire to secure by Letters Patent, is:

An educational device comprising a base, an upright connected thereto having a vertical slot formed therein, a member having columns of characters thereon rotatably mounted on the base, and a slide on the upright for varying the amount of exposure of the column of characters through the slot.

In testimony whereof I affix my signature, in the presence of two witnesses.

JOHN G. WARFIELD.
